KEEPER PLATE FOR A DOOR CATCH

Frank Mestre, R.D. 1, Box 108, Rhinebeck, N.Y. 12572

Filed July 15, 1974, Ser. No. 488,287

Term of patent 14 years

Int. Cl. D8—07

U.S. Cl. D8—137

FIG. 2

FIG. 1 is a front perspective view looking from a point thereabove of a keeper plate for a door catch showing my new design thereof; and

FIG. 2 is a sectional view of my new keeper plate design taken along line 2—2 of FIG. 1.

I claim:

The ornamental design for a keeper plate for a door catch, as shown.
